REEL FOR ROLLING MILL

Joseph M. O'Malley, Worcester, Mass., assignor to Morgan Construction Company, Worcester, Mass., a corporation of Massachusetts

Application October 5, 1953, Serial No. 384,198

3 Claims. (Cl. 242—81)

This invention relates to a reel and more particularly to an apparatus for coiling the product of a rolling mill.

In the process of forming thin rolling mill product, such as rod, it is the usual practice to form it into coils in a reel. These reels are of two types: the pouring reel, wherein the rod enters a cylindrical cage from a fixed nozzle and the cage rotates about a vertical axis and the laying reel, wherein the cage remains fixed and the nozzle moves in a circle about the axis of the cage. In both cases, but particularly in the case of the pouring reel, the effects of centrifugal force prevent efficient operation at very high speeds. As the speed of production of rod from rolling mills increases, as it has in the last few years, this force becomes more and more troublesome, since centrifugal force increases as the square of the velocity. The most predominant effect of this force in a pouring reel is that the rod sticks to the pins making up the cage at the point at which the rod enters the reel instead of sliding downwardly to rest on the top of the portion of the coil already formed. This is because the centrifugal force presses the rod against the pins with such force that the friction forces resisting downward movement of the rod are greater than the force of gravity tending to move the rod downwardly. This tendency limits the speeds at which rod may be reeled at the present time. The present invention obviates some of the difficulties encountered in prior art constructions because of these effects.

It is therefore an outstanding object of the present invention to provide a reel which will enable thin products of a rolling mill to be formed into a coil at a considerably faster rate than has been possible previously.

It is a further object of this invention to provide a pouring reel in which the friction forces tending to prevent the rod from moving downward are minimized.

Another object of the present invention is the provision of a pouring reel in which centrifugal forces are used to overcome frictional forces that might otherwise prevent downward movement of the rod.

To the accomplishment of the foregoing and related ends, the invention, then, comprises the features herein-after fully described and particularly pointed out in the claims the following description and the annexed drawing setting forth in detail a certain illustrative embodiment of the invention, this being indicative, however, of but one of the various ways in which the principles of the invention may be employed.

In the said annexed drawing, Fig. 1 is a vertical sectional view of a reel constructed after the teachings of the invention, and

Figure 2 is a sectional view taken on the line II—II of Figure 1.

In general, the invention consists in constructing a pouring reel in such a manner that the pins are inclined inwardly and upwardly while rod is being admitted, but which move into a vertical position when the rod coil is being removed.

Referring to the drawing, the reel, designated generally

2

by the reference numeral 10, comprises a horizontal coil plate 11 through which pass a circular row of inner pins 12 and a circular row of outer pins 13. The pins are fastened to a driving plate 14 which underlies the coil plate and serves to support and drive it. A housing 15 surrounds all of these elements. The driving plate 14 is mounted on and concentric with a hub member 16 which has a tubular portion 17 which extends downwardly and a skirt portion 18 which extends downwardly and outwardly. The lower edge of the skirt has a bevel pinion gear 19 fastened thereto. The pinion gear engages another bevel gear 20 keyed to a horizontal drive shaft 21. This shaft is, in turn, connected to a source of power, not shown, but by which the reel is driven. A housing 22 surrounds the gears and serves to support the elements of the reel. The hub member 16 is supported on the housing 22, there being a combined thrust and radial bearing 23 therebetween. Through the tubular portion 17 of the hub member extends a shaft 24 which is fastened at its upper end to the coil plate and at its lower end to an actuating mechanism, not shown, which on occasion causes the shaft to move upwardly, carrying the coil plate with it.

The inner pins 12 taper to a reduced diameter at the upper portion. At the lower end, each is provided with a threaded portion 25 which extends through the drive plate and on which is threaded a nut 26. An integral circular flange or shoulder 27 extends outwardly from the pin above the threaded portion and is eccentric therewith; this shoulder resides in a circular aperture 28 provided on the coil plate during reeling. Drive pins 29 extend upwardly from the drive plate and pass through suitable apertures 30 in the coil plate. Fastener pins 31 pass through the hub member and the drive plate to hold them together, the pins passing axially upwardly through each of the drive pins 29 and having a nut 32 at the upper end thereof.

Each of the outer pins 13 is provided at its lower end with a flat portion 33 which lies between two lugs 34 projecting downwardly from the underside of the driving plate 14 and is hingedly connected thereto by a pivot pin 35. The pivot pins are arranged substantially horizontally and tangentially to an imaginary circle whose center is coincident with the axis of the reel. Immediately above and integral with the flat portion 33 of each outer pin 13 is a flange or flat disk portion 36 whose axis passes centrally of the pivot pin 35 and the flat portion. Above and integral with the disk portion 36 is a circular hub 37 which is concentric the disk portion; thus hub resides in an aperture 38 in the coil plate 11, this aperture, however, being considerably larger than the hub. Above the hub and integral therewith is a shaft portion 39 of the pin. This shaft portion is of elongated right conical shape and is eccentric with the hub 33 and the disk portion 36; furthermore, the axis of the shaft portion is inclined at a small angle to the axes of the hub and disk portion, this inclination being in the direction of the said axes and of the main axis of the reel. This angle will, of course, be determined by such factors as the speed of reeling, the size and weight of the material, etc.

The operation of the apparatus of the invention will now be evident in view of the above description. Power is introduced through the shaft 21, thus driving the bevel gear 20 which is keyed thereto. The gear 20 engages the pinion gear 19 so that the hub member 16, to which it is fastened, is also driven. This, in turn, drives the driving plate 14 because of the presence of the fastener pins 31 which extend through the driving plate and the hub member. The rotation of the driving plate carries with it the inner pins 12, because they are fastened tightly thereto; it carries with it the outer pins 13 because

of the connection through the lugs 34 and the pins 35. The coil plate 11 is also carried along with the driving member because of the engagement of the drive pins 29 with the sides of the apertures 38 in the coil plate. The coil plate is also driven by the engagement of the shoulder 27 of each inner pin 12 with the vertical surface of the respective aperture 28 in the coil plate and by the engagement of the hub portion 37 of each outer pin 13 with the surface of its respective aperture 38 in the coil plate. The shaft 24 is in the lower, retracted position shown in solid lines in the drawing and, so the coil plate 11 is drawn into engagement with the upper surface of the driving plate 14. Because of the relationship of the parts, however, actual engagement takes place only between these two members and the disk portion 36 of the outer pins; that is to say, the disk portion is clamped between the driving plate and the coil plate under the combined actions of the shaft 24, the weight of the coil plate, and the weight of any rod which may be resting on the coil plate. This clamping of the disk portion constrains it to a generally horizontal position, so that the shaft portion 39 of each of the outer pins leans inwardly toward the center of the reel. The rod is introduced into the space between the inner and outer pins from a fixed nozzle, not shown. As the rod accumulates in this space, it is thrown outwardly against the outer pins by centrifugal force. In the past, as has been explained, a speed of reeling is eventually reached under a given set of conditions at which the friction forces resisting downward movement of the rod are greater than the forces of gravity tending to force the rod down. When this condition is reached, it is impossible to coil the incoming rod. In the present apparatus, however, the centrifugal forces break down into two components: one component normal to the pin surface which tends to create friction forces and to resist downward movement of the rod and another component parallel to the pin surface which aids the force of gravity in forcing the rod downwardly. If the speed of the reel is greatly increased, a point will be reached, even with the apparatus of the invention, wherein the friction forces become too great to be overcome by gravity. However, the present invention permits reeling speeds which are greatly in excess of those possible with prior art devices.

When sufficient rod has accumulated in the space between the inner and the outer pins, the reel is stopped and the shaft 24 is moved into the upper position shown in broken lines and indicated by the reference numeral 24'. This carries the coil plate and the coil into the position indicated by the reference numeral 11'. The upward movement of the coil plate 11 releases the disk portions 36 of the outer pins 13, so that the outer pins are free to rotate about the pivot pins 35 to the extent permitted by the apertures 38. The coil of rod which was previously formed is slightly conical, with the larger end at the bottom, because of the inward inclination of the outer pins. The large end of the coil now engages upper portions of the outer pins, thus camming the pins outwardly. The pins, thus, move outwardly until prevented from further movement by engagement with the surfaces of the apertures 38. In this position, the outer pins are substantially vertical, as is indicated by the reference numeral 13'. The pins are, therefore, rigidly

situated in their inwardly inclined positions during the formation of the coil, but are free to move into vertical positions for the removal of the coil from the reel.

Other modes of applying the principle of the invention 5 may be employed, change being made as regards the details described, provided the features stated in the following claims, or the equivalent of such, be employed.

I therefore particularly point out and distinctly claim as my invention:

10 1. A pouring reel for use in coiling the product of a rolling mill comprising a first series of pins arranged in a circle, a second series of pins arranged in a circle which is concentric with the first circle and whose diameter is substantially larger than the first, the two series of pins defining an annular space within which the coil is formed, means for rotating the product and the pins relative to each other about an axis passing through the center of the pin circles, the pins in the second circle being hingedly mounted on pivotal axes which are tangential to a circle concentric with the said axis for movement between positions inclined to the axis and positions parallel to the axis.

25 2. A pouring reel for use in coiling the product of a rolling mill comprising a first series of pins arranged in a circle, a second series of pins arranged in a circle which is concentric with the first circle and whose diameter is substantially larger than the first, a coil plate through which the pins project, the two series of pins and the coil plate defining an annular space within which the coil is formed, means for rotating the product and the pins relative to each other about an axis passing through the center of the pin circles, the coil plate being capable of movement along the axis for removal of the coil, the pins in the second circle being pivotally mounted for movement from positions inclined to the axis to positions parallel to the axis when the coil plate is in the coil removal position.

30 3. A pouring reel for use in coiling the product of a rolling mill comprising a driving member, a coil plate overlying the driving member and capable of movement

40 toward and away from the member, a first series of pins extending through the plate and arranged in a circle, a second series of pins extending through the plate and arranged in a circle which is concentric with the first circle having a diameter which is substantially larger than the

45 first, the two series of pins and the plate defining an annular space within which the coil is to be formed, means for rotating the product and the pins relative to each other about an axis passing through the center of the pin circles, the pins in the second circle being hingedly connected to the driving member and each having a flange

50 which is clamped between the said member and the plate when the member and plate are in juxtaposition, the pins in the second circle being held in fixed positions which are inclined to the said axis when their flanges are so clamped, but being capable of movement to positions parallel to the said axis when the coil plate moves away from the plate.
